U.S. CL. 102—65.2

1 Claim

ABSTRACT OF THE DISCLOSURE

The invention relates to a grenade to be launched by means of a bullet from a rifle on the end of the barrel of which a tubular tail of the grenade is fitted, said bullet striking an axial obstacle carried by the grenade. The grenade further comprises an auxiliary propelling charge delivering powder gases through annular nozzle means opening toward the rear, and igniting means extending from the axial obstacle to said auxiliary propelling charge.

The present invention relates to grenades to be launched by means of a firearm (for instance a rifle), such a grenade being fitted, in launching position, on the end of the rifle barrel and launching proper being performed by firing a bullet, which is generally, but not necessarily, of the type normally used with this rifle.

The object of the present invention is to provide a grenade of this kind which is better adapted to meet the requirements of practice than those known up to now and in particular a grenade comprising auxiliary propelling means which improve the performance obtained.

Such a grenade comprises a supporting sleeve located at the rear of the grenade and adapted to fit on the outer surface of the front end of the launching gun barrel, said sleeve carrying advantageously in the front part thereof, an axial obstacle capable of collecting and transmitting to the grenade the impulse produced by the impact of a bullet fired by the rifle.

According to the present invention, the grenade further comprises an auxiliary propulsion charge located coaxially on the outside of said supporting sleeve, preferably at the level of said axial obstacle, and igniting means extending from said axial obstacle to said auxiliary propulsion charge, said igniting means being adapted to be operated by the impact of the launching bullet on said axial obstacle.

Preferred embodiments of the present invention will be hereinafter described with reference to the appended drawings given merely by way of example and in which,

FIG. 1 is a diagrammatic elevational view, with parts in section, of a grenade according to this invention;

FIG. 2 is a perspective view illustrating a modification;

FIG. 3 is another perspective view illustrating another modification.

The grenade according to this invention, an embodiment of which is shown by FIG. 1, includes an intermediate body 1 extending frontwardly to form a war-head 2 and provided, rearwardly thereof, with a supporting sleeve 3 adapted to fit on the front end of the launching rifle barrel (which may carry an accessory such as a muzzle brake or a flame shield). Sleeve 3 may carry fins 4.

This grenade is provided with an axial obstacle 5, for instance of steel, for collecting and transmitting to the grenade the impulse resulting from the impact on said obstacle of a launching bullet fired from the rifle. The obstacle 5 is rigid with, that is, immovable with respect to the sleeve. Said obstacle consists for instance of a frusto-conical piece housed in the front part of sleeve 3. The

2

large base of said frusto-conical piece is at the rear and the small base, provided with a fixation flange 5a, at the front.

Now, according to the main feature of the present invention, the grenade further comprises the following elements:

Auxiliary propelling means 6 ("booster" means) capable of improving the performance of the grenade and disposed on the outside of sleeve 3 and coaxially therewith, preferably, as shown, in the front portion of said sleeve, between the front end thereof and the center of gravity G of the grenade, and

15 Igniting means extending from axial obstacle 5 to auxiliary propelling means 6, said igniting means being adapted to be operated by the impact of the launching bullet on axial obstacle 5.

Auxiliary propelling means 6 are advantageously arranged to include a propellant charge symmetrically disposed about the axis of the grenade, the gases from said charge flowing out through at least one nozzle 6a.

Auxiliary propelling means 6 may include:

Either an annular propellant charge made of a single block and adapted to feed combustion gases either to a single annular nozzle or to several circular nozzles disposed in a circular row at equal intervals from one another,

Or a propellant charge made of several similar elements disposed in a circular or closed polygonal row at equal intervals from one another, which elements may feed combustion gases either to a single annular nozzle or to several circular nozzles disposed in circular row at equal intervals from one another. In particular every propellant element may feed its combustion gases to a corresponding nozzle.

On the other hand, when the auxiliary propelling means 6 include several nozzles 6a disposed in circular row, it is advantageous, according to another feature of the present invention illustrated by FIG. 2, to arrange at least some of these nozzles 6a (in particular by suitably inclining the nozzle axis, at least in the downstream portion thereof) in such manner that the velocity V of the propelling streams issuing from the nozzles has a tangential component V_t extending in the same relative direction for all of said nozzles. In this case said components V_t impart to the grenade, as soon as the auxiliary propelling charge is ignited, a stabilizing gyratory movement about the grenade axis.

In both cases, i.e., either when auxiliary propelling charge 6 includes several circular nozzles disposed in a circular row or when said auxiliary propelling charge includes a single annular nozzle, it will be of advantage, according to another feature of the invention, to arrange said annular nozzle or said circular row of nozzles in such manner that the total propelling stream issuing from auxiliary propelling means 6 forms a frusto-conical sheet (either continuous or discontinuous) converging, at least approximately, toward a point P located at the rear of, and preferably close to, the center of gravity G of the grenade.

60 This means that the nozzle or nozzles 6a are arranged so that, at any point of the outlet section of the propelling stream forming a frusto-conical sheet, the discharge velocity V has a radial component V_r .

According to the preferred embodiment of the invention illustrated by the drawings, according to which auxiliary propelling means 6 is disposed at the rear of the center of gravity G of the grenade, the arrangement of the nozzle or nozzles 6a will be such that the radial component V_r is directed outwardly and has an intensity such that the convergence point P is located slightly at the rear of the center of gravity G.

This last mentioned feature of the invention consider-

ably reduces the risks of an increased dispersion in the case where the output of some nozzles (or of some sectors of an annular nozzle) would be accidentally greater than the output of other nozzles or nozzle sectors.

This lack of symmetry of the outputs involves a bending in a given direction of the trajectory of the grenade but owing to the fact that the point of convergence P is located at the rear of the center of gravity G, the grenade then pivots about said center of gravity in a direction opposed to that in which the trajectory has been bent, that is to say, in a direction moving its axis toward the direction of the firing axis. It follows that, as soon as the combustion of auxiliary propelling means 6 is finished, it will suffice to obtain a slight swinging of the grenade to return it in the direction of the firing axis, this slight swinging being quickly ensured by the tail unit 4 of the grenade.

It will be possible to combine the benefits of the above mentioned second and third features. This result may be obtained, for instance,

Either by arranging the nozzles of a circular row of nozzles alternately according to said second and to said third feature,

Or by providing two concentric annular rows of nozzles disposed respectively according to the second feature and to the third feature,

Or again, by arranging similarly all the nozzles of an annular row in such manner that the output velocities have both a tangential component V_t and a radial component V_r , which corresponds to substituting for convergence point P a circumference having its center at said point and located in a transverse plane, the respective lines of the vectors representative of the output velocities V passing through different points of said circumference.

Concerning now the igniting means to be operated by the firing of the launching bullet, they may be made as follows:

An ignition relay is provided between auxiliary propelling device 6 and a primer or the like 7 carried by axial obstacle 5 and preferably located near the front of said axial obstacle.

This ignition relay may advantageously include a transmission charge 8 consisting of an incendiary composition located immediately at the front of primer 7, said transmission charge 8 being in communication through at least one radial conduit 9 (and preferably several such conduits) with the ignition surface S of auxiliary propelling charge 6.

The casing of said propelling 6 may be provided with at least one safety valve 10 or the like.

Finally, according to still another feature of the invention, the firer's eyes may be protected from the flames issuing from the nozzle or nozzles 6a, by providing at the rear of said nozzle 6a a baffle 11 (shown in dot-and-dash lines in FIG. 1), this baffle converging toward the rear and causing the gases issuing from the nozzle or nozzles to move toward socket 3.

A grenade made according to the present invention is relatively short because the location of the booster on the outside of the supporting sleeve does not make it necessary to overdimension said sleeve in the axial direction.

The device does not produce an increase of the recoil, owing also to the external position of the booster.

The dispersion is reduced owing to the fact that the booster is located in the vicinity of the center of gravity of the grenade.

Finally, the vision of the firer is not impeded if the grenade is provided with a baffle as above described.

In a general manner, while the above description discloses preferred embodiments of the invention, it should be well understood that said invention is not limited thereto as there might be changes made in the arrangement, disposition and form of the parts without departing from the present invention.

What I claim is:

1. An improved grenade which comprises, in combination, a body, a sleeve of revolution rigid with the rear part of said body, said sleeve including a cylindrical rear extension adapted to fit on the end of the barrel of a launching rifle, and an axial obstacle immovable with respect to said sleeve adapted to receive and to transmit to said body the impact of a bullet fired from the launching rifle, said obstacle comprising a generally frusto-conical piece disposed with its small base towards the front, an auxiliary propulsion means carried by said sleeve, including a powder charge surrounding said sleeve coaxially thereto and close to said obstacle, and igniting means extending between said obstacle and said powder charge and operative by a launching bullet striking said obstacle, said igniting means comprising a primer located near the front of said generally frusto-conical piece.
